TENSIONING DEVICE

Filed May 7, 1928

UNITED STATES PATENT OFFICE

EDWARD HANO, OF HOLYOKE, MASSACHUSETTS, ASSIGNOR TO PHILIP HANO COMPANY, INC., OF NEW YORK, N. Y., A CORPORATION OF MASSACHUSETTS

TENSIONING DEVICE

Application filed May 7, 1928. Serial No. 275,935.

This invention relates to tensioning devices and in particular to one adapted for use in connection with the tensioning of paper to be operated upon by a writing machine.

5 A particular object of the invention is to provide a simplified tensioning device which may be used in connection with webs of paper arranged to be fed from folded piles or from rollers into the writing machine.

10 A still further object of the invention is to provide a tensioning device which is adjustable so that the webs of paper can be properly aligned to be fed to the writing machine in register, the tension being maintained on the 15 paper through the medium of suitable rollers and contact plates.

To enable others skilled in the art to fully comprehend the underlying features of my invention that they may embody the same in 20 the various modifications in structure and relation contemplated, a drawing depicting a preferred form has been annexed as a part of this disclosure and in such drawing, similar reference characters denote corresponding 25 parts throughout all the views, of which,

Figure 1 is a view in side elevation, a part thereof being shown in section to illustrate the construction of my improved tensioning device, the same being shown in its application 30 to a writing machine and being positioned to feed into the writing machine, the paper in web formation.

Figure 2 is a top plan view of the tensioning device.

35 Figure 3 is an enlarged view in sectional elevation of the rear end of the tensioning device, the method of mounting the slides and rollers being clearly shown, and

Figure 4 is a section taken on the line 4—4 40 of Figure 3 and illustrates how the rolls and shelves are mounted in the tensioning device.

Referring to the drawings in detail, 5 indicates a writing machine of any character which is arranged to have fed through one 45 side thereof, paper in web formation 6, the paper being drawn from suitable rolls 7 which are carried on a roll holder 8 and which is supported in connection with the tensioning device through the medium of a suitable roll holding brackets 9. Inasmuch as two would

be used to support the opposite ends of the roll or roll holder, these roll holding brackets are each secured to the bottom 10 of the frame 11 of the tensioning device, the frame being constructed of substantially rectangular 55 housing 12 which forms the longitudinal sides of the device and which are connected together at their ends through the medium of the suitable cross plates 13 and 14, both of which are of angular formation, the forward 60 one 13 being arranged to rest in any suitable portion of the writing machine so that the webs of paper may be drawn thereinto in proper alignment.

If desired, the rectangular side pieces or 65 frames 11 may be separated so that one portion thereof indicated by the numeral 16 may constitute a removable cover, although any desired construction may be employed in this instance. The side frames, in their depending portions 17, as illustrated in Figure 3, carry the hereinbefore mentioned roll bracket 9 which is secured thereto through the medium of the rivet 18. These depending portions of the frame also are arranged to hold 70 the angle members 19 upon which are supported the plate or shelves 20. These plates or shelves 20 are arranged to be engaged by the rollers as will be hereinafter described.

The frames 10, at their opposite, inner sides, 75 are provided with the headed rivets or cam pins 21, these cam pins extending through cam slots 22 formed in slides 23 mounted within the frames and due to their mounting on the pins 21, being arranged for forward sliding 80 movement relatively to said frame. The inner side walls 24 of the frames are undercut as at 25 and adjacent the outer end of said 85 undercut portion, are provided with the notch 26. The outer ends of the slide 23 are provided with elongated slots 27 in which is disposed the reduced end 28 of the pull bar 29. Access to the pull bar is provided 90 through the medium of a cut out 30 in the rear connecting plate 14 and it is quite evident that when the extensions 28 of the pull bar 29 are not resting in the notches 26 of the side walls 24, the sides 23 will be moved toward the opposite end of the device through 95 the medium of the slide springs 31 which con-

100

nect the ends of the slides with the cross frame piece 13.

It is quite evident, too, that when the frame pieces are drawn forwardly or toward the writing machine by the springs 31, there being one of these springs provided for each of the slides, that the curvature of the cam slot 22 in said slide, will cause depression of the slide, thus carrying the tensioning rollers 32 into position against the plate or shelves 20. This is clearly illustrated in Figure 3, in which the upper edge 33 of the slides are cut to provide stops 34 against which the end 35 of the rollers 32 abut, thus preventing movement of the rollers relatively to the slides.

It will be noted, also, that the outer ends of the extensions 35 of the rollers are grooved as at 36 to provide seats for the roller springs 37 which tend to maintain the rollers 32 in yieldable relation with the slides, thus giving them a floating effect when they are in contact with the plate 20, so that the paper passed over the plate or shelves 20 and beneath the rollers 32 will be tensioned during its feed into the machine.

It is evident that there is a cross plate or shelf 20 provided for each of the rollers 32 and when the pull bar is not in its locking position as shown in Figure 3, these rollers will be resting upon the plate 20, due to the cam slot 22 forcing the slides downwardly to carry the rollers on to the plates 20. This is clearly illustrated in Figure 1 and in this instance the springs 37 yieldably retain the rolls 32 in position against the plates or cross shelves 20.

It is of course understood that while I have indicated a roll from which the length of paper may be drawn, it is to be distinctly understood that the method of handling the paper whether in roll or in folded form is immaterial to my invention, the operating parts of the device and construction thereof cooperating with the paper after it is fed into the tensioning device to permit the same to be properly fed into the writing machine in alignment and in register.

It is quite evident, therefore, that I have provided a tensioning device which is adaptable for use in connection with a writing machine into which paper in fan fold formation or in superposed web formation is to be fed for the making of copies and a device which can be manufactured at small cost, has few operating parts and which will effectively place the same tension on all of the webs of paper passing therethrough.

It is also evident that I have provided a device wherein the tension may be released by the withdrawal of the rolls from their holding plates and one in which the rolls may be locked in their non-engaging position so that the webs of paper may be properly fed through the device and may be placed in

alignment after which the rolls may be released to engage the webs so aligned.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention what I claim as new and desire to secure by United States Letters Patent is:—

1. A tensioning device for use in permitting the feed of paper in web formation to a writing machine comprising a main frame having notches therein, pins on the main frame, a movable frame having cam slots therein with which the pins are in engagement, rollers supported solely on the movable frame, shelves for the rollers, stop extensions on said movable frame for limiting the movement of the rollers relative to the said frame, springs for yieldably maintaining the rollers against said extensions, a spring for normally urging the movable frame in one direction and bringing the rollers into engagement with the shelves, and a locking bar carried by the movable frame and arranged to drop into the notches of the main frame for preventing operation of the movable frame by its spring.

2. A tensioning device comprising a main frame, pins on the main frame, a movable frame having cam slots therein in which said pins engage, a plurality of rollers mounted solely on the movable frame, a shelf for each of said rollers and a spring for normally urging the movable frame in one direction whereby the cam slots will cause the rollers to be positioned on said shelves.

3. A tensioning device comprising a main frame, pins on the main frame, a movable frame having cam slots therein in which said pins engage, a plurality of rollers mounted solely on the movable frame, a shelf for each of said rollers carried on said main frame, a spring for normally urging the movable frame in one direction whereby the cam slots will cause the rollers to be positioned on said shelves and springs for yieldably holding the rollers on said shelves.

In testimony whereof I affix my signature.

EDWARD HANO. [L. S.]
